Primary Examiner — Antoine D Davis(74) *Attorney, Agent, or Firm* — Boyle Fredrickson, S.C.(57) **CLAIM**

The ornamental design of a torpedo level, as shown and described.

DESCRIPTION

FIG. 1 is an isometric view of a first embodiment of a torpedo level incorporating my new design, wherein the portions in phantom form no part of the claimed design;
FIG. 2 is a right side elevation view thereof;
FIG. 3 is a left side elevation view thereof;
FIG. 4 is a bottom plan view thereof;
FIG. 5 is a top plan view thereof;
FIGS. 6 and 7 are and elevation views thereof;
FIG. 8 is an isometric view of a second embodiment of a torpedo level incorporating my new design, wherein the portions in phantom form no part of the claimed design;
FIG. 9 is a right side elevation view thereof;
FIG. 10 is a left side elevation view thereof;
FIG. 11 is a bottom plan view thereof;
FIG. 12 is a top plan view thereof; and,
FIGS. 13 and 14 are and elevation views thereof.
